UNITED STATES PATENT OFFICE.

CHARLES L. JACOBY, OF MINNEAPOLIS, MINNESOTA.

APRON AND SUPPORT THEREFOR.

SPECIFICATION forming part of Letters Patent No. 392,676, dated November 13, 1888.

Application filed June 20, 1888. Serial No. 277,669. (No model.)

To all whom it may concern:

Be it known that I, CHARLES L. JACOBY, of Minneapolis, in the county of Hennepin and State of Minnesota, have invented certain 5 Improvements in Apron-Supports and Aprons to be secured thereto, of which the following is a specification.

My invention relates to improvements for readily securing an apron to the person for 10 the protection of clothing when the occupation of the wearer makes it necessary or convenient to provide such protection and prevent contact with the clothing and the bench or table at which he is working, and for securing 15 the apron to the support.

My invention consists in providing a device which may be quickly applied to the person to hold the apron in any desired position, and to which the apron may be quickly attached 20 or removed, and in an apron attached thereto, as hereinafter described, and specified in the claims.

In the drawings which form part of this specification, Figure 1 is a side elevation showing my apron and apron-support. Fig. 2 is a 25 section on line $\alpha\alpha$ of Fig. 1. Fig. 3 is a plan, and Fig. 4 is a detail section showing the manner of applying the apron to the support.

In the drawings, 2 represents the apron, 30 made of any suitable material and of any convenient size and shape to properly protect the clothing over which it is worn. The upper edge of the apron is formed into a shirr or casing, 3, through which the spring 4 is passed.

The spring 4 may be constructed of any suitable material, preferably of metallic wire, as this will be more easily constructed and will hold its form better, while being capable of being easily spread or extended. A tip or 40 knob, 6, is preferably placed on each of the free ends of the spring to prevent the catching or wearing, which might occur if the corners were left square or sharp.

The spring 4 is provided, preferably on its 45 outer surface and at a point near each end, with a button, 5, which is preferably secured firmly to the spring.

The apron is provided near each end of the shirr with a button-hole, 7, adapted to be engaged with the button 5. The casing 3 at the 50 top of the apron is of sufficient size to permit the knobs 6 and buttons 5 to be passed through it, as shown in Fig. 4, so that the apron may be readily placed upon or removed from the spring without cutting or breaking the stitches 55 that form the casing. The buttons secure the apron upon the spring at the desired point. The wire is smooth and without projections, so that it will readily slide through the casing.

It will be seen that in order to adjust the 60 device the spring 4 should be spread or opened until its free ends are sufficiently far apart to allow them to pass the waist of the wearer. When the apron has been adjusted to its proper position, the spring 4 is released, and its 65 tension causes it to clasp the waist and hold the apron securely in place. The apron accommodates itself to the size of the wearer, and the apron may be held in any desired position either about the waist or chest. 70

I claim as my invention—

1. The spring-band 4, composed of metallic spring-wire having rounded ends and provided at a point near each end on its outer face with buttons 5, in combination with the 75 apron 2, formed with the shirr 3, of sufficient size to pass over said buttons, and having the button-holes adapted to receive said buttons, substantially as and for the purposes specified.

2. The spring-band 4, composed of metallic 80 spring-wire provided at its ends with knobs 6 and at a point near each end with the buttons 5, in combination with the apron 2, formed with the shirr 3, of sufficient size to pass over said knobs and buttons, and having the button-holes adapted to receive said buttons, substantially as and for the purposes specified. 85

In testimony whereof I have hereunto set my hand this 10th day of April, 1888.

CHARLES L. JACOBY.

In presence of—

R. H. SANFORD,
A. M. GASKELL.
